PROGRAM CONTROL RECEIVER

Winfield R. Koch, Haddonfield, N. J., assignor to
Radio Corporation of America, a corporation of
Delaware

Application July 24, 1942, Serial No. 452,173

1 Claim. (Cl. 250—20)

My present invention relates to program control systems, and more particularly to a frequency modulation communication system employing program-selective control tones.

It is often desired on the part of the receiver operator, especially in the broadcast band, to cut out receiver reproduction during announcement periods. This type of program control is of especial desirability during music program transmission. Further, the broadcast listener often objects to the fact that "speech-music" control switches, such as acoustic compensation and fidelity control switches, must be operated manually and at the receiver control panel. It would be highly desirable to provide a method of automatically monitoring the program arriving at the broadcast receiver so as to secure the aforementioned characteristics. Frequently modulation of the present day type lends itself to such monitoring.

It may be stated to be one of the main objects of my present invention to provide a radio communication system wherein a control, or monitor, tone is transmitted along with modulation desired to be discriminated against at the receiver, and the control tone being utilized at the receiver to effect one or more control functions with respect to the modulation on the received carrier.

Another important object of this invention is to provide a method of automatically preventing receiver response during "announcement" periods of a program broadcast; a special monitor tone being included on the carrier during such periods.

Another object of my invention is to provide a broadcast receiver wherein the listener is permitted to hear only announcements, such as news bulletins, and not the musical program.

Another object of my invention is to provide automatic acoustic compensation control and/or fidelity control at a broadcast receiver in response to the reception of a special monitor tone of super-audible frequency.

Yet another object of my invention is to provide a frequency modulation system wherein a super-audible monitor tone is included in the modulation during such periods of transmission when a particular type of program control is desired.

Still other objects are to improve generally the efficiency and reliability of program control systems, and more especially to provide such control systems in frequency modulation receivers.

The novel features which I believe to be characteristic of my invention are set forth with particularity in the appended claims; the invention

itself, however, as to both its organization and method of operation will best be understood by reference to the following description taken in connection with the drawing in which I have indicated diagrammatically several circuit organizations whereby my invention may be carried into effect.

In the drawing:

Fig. 1 schematically shows an FM (frequency modulated carrier wave) transmitter system embodying the invention; and

Fig. 2 shows an FM receiver employing the invention.

Referring now to Fig. 1, there is shown a transmitting system of the FM type. The generic term "angular velocity-modulated carrier wave" is used herein to denote that either frequency, or phase, modulation may be employed. The present system of control with a super-audible monitor tone lends itself particularly to high deviation range FM communication. In the latter the master oscillator 1 operates at some carrier frequency in the assigned ultra-high frequency band of 42 to 50 megacycles (mc.). The frequency modulator 2 is usually an electronic reactance device which is connected across the oscillator tank circuit to vary the oscillator frequency with respect to a center frequency which is the unmodulated carrier frequency value. The magnitude of the electronic reactance is varied by the applied modulation.

Thus, the program microphone 3 feeds the modulation amplifier 4 with the usual music or other audible program material. The switch 6—5 being closed, the amplified modulation energy is fed through a further amplifier 7 to the reactance tube 2. The latter is so constructed that the carrier frequency is deviated in accordance with the modulation amplitude; the rate of deviation is a function of the modulation frequencies per se. In the presently-assigned FM band the channel width is 200 kilocycles (kc.), but the transmitter actually deviates the carrier a maximum of 75 kc. either side of the transmitter mean frequency.

During the course of a program, such as music, there will be announcing periods. Usually the announcer's microphone 8 feeds an amplifier, which is connected in turn to the contact 10 of switch arm 6. Thus, closure of switch 6—10 permits the modulation applied to modulator 2 to be from solely source 8, while source 3 is concurrently cut off. A control tone is fed into amplifier 9 from pilot tone oscillator 11. The latter operates at a super-audible frequency, say 22 kc. Both oscillators 11 and 1 operate with constant am-

plitude. It will now be seen that when the announcing switch 6-10 is closed the speech and control tone are utilized as composite modulation. The reactance device at 2 is varied in accordance with output of amplifier 9. Since the channel is at least 150 kc. wide, the super-audible control tone is readily utilized in the transmission. The F. M. wave energy is amplified by power amplifier 12, and radiated by the antenna 13.

Of course, the sources 3 and 8 may be respectively music and speech for different sequences of a long broadcast schedule. The sources may be located in separate studios, and the switch device 6-5-10 may then be used as a change-over switch from one program to another. At the receiver the collector 14, which may be a dipole, feeds the collected FM wave energy to a radio frequency amplifier 15. The latter may include one or more selector circuits each tuned to the mean, or carrier, frequency of the collected wave energy. The converter 16 reduces the center frequency to an operating I. F. value, and the latter may be 4.3 mc. After intermediate frequency (I. F.) amplification at 17, the energy is subjected to the action of an amplitude limiter 18. The latter functions to eliminate any amplitude modulation effects which may arise in the receiving system.

The FM detector 19 may be of any well known form, and the function of the detector is to derive from the FM wave energy the modulation which was applied to the master oscillator at the transmitter. Where the switch 6-5 is closed, the modulation output of the detector 19 would correspond to the modulation applied to the program microphone 3. Where the switch 6-10 of Fig. 1 is closed, then the modulated output of detector 19 would comprise the announcing modulation and the control tone.

The audio amplifier 21 is preceded by a low pass filter 20. Preferably the latter is constructed to pass audio frequencies over an audio range up to about 15,000 cycles, and cuts off sharply thereafter. In this way the super-audible control tone is prevented from passing through to the audio amplifier 21. Successive audio amplifiers 22 and 23 may be arranged in cascade with the output terminals of amplifier 21. The output transformer of amplifier 23 may be connected to any desired type of reproducer. Those skilled in the art are fully acquainted with the manner of constructing networks 14 to 23 inclusive, and, therefore, they are schematically represented.

The monitoring circuit comprises the bandpass filter 25 having its input terminals connected to the output terminals of detector 19 by a path 24. In other words when the 22 kc. control energy exists in the output of the detector 19, the energy is transmitted over path 24 to filter 25. The filter 25 may have a passband width which is relatively narrow so that only the energy of super-audible frequency will pass to the amplifier 26. After amplification the super-audible control energy is applied to a pair of transformers 27 and 28.

The primary windings of the two transformers may be arranged in series in the plate circuit of amplifier 26. The secondary of transformer 27 has one side connected to the cathode of diode rectifier 29, while its opposite end is connected to one end of load resistor 30, which is also connected to the negative terminal of bias source 40. The load resistor 30 is bypassed for alternating current components by condenser 31. The anode end of resistor 30 is connected to a contact 36. The secondary of transformer 28 has one

end connected to the anode of diode rectifier 32, while the opposite end is connected to the lower end of load resistor 33. The latter is bypassed by alternating current components by condenser 34. The lower end of resistor 33 is connected to the negative terminal of a source of high negative biasing potential 35 whose positive terminal is grounded. The cathode end of resistor 33 is connected by lead 50 to a contact 37.

The audio frequency amplifier 21 may have a gain control electrode thereof, such as the signal input grid, connected to the adjustable control switch arm 39. The contact 38 is provided in spaced, intermediate relation to contacts 36 and 37. Contact 38 is connected to the negative terminal of negative biasing source 40, the latter having its positive terminal grounded. Switch arm 39 is adjustable, and can be connected in electrical contact with point 36, point 38 or point 37. Switch 39 is, therefore, the "announcement control switch." Assuming that switch arm 39 is in contact with point 38, then the audio amplifier 21 will be operating in normal fashion since the source 40 applies normal bias to the amplifier. In that case the modulation from either of sources 3 or 8 will be heard. This follows because there is no control applied to amplifier 21, even though the control tone exists on the carrier when the switch 6-10 is closed.

If, now, the switch arm 39 is adjusted to point 36, only the program modulation from source 3 will be heard and announcements from source 8 will be deleted. This occurs because when switch 6-10 is closed, the control tone is superposed on the carrier. At the receiver the rectifier 29 rectifies the control tone energy, and provides a direct current voltage across resistor 30 whose magnitude is sufficiently high to bias audio amplifier 21 to cut-off. As soon as the switch 6-10 is open, and switch 6-5 is closed, the program from source 3 is received, but no control action is applied to amplifier 21 from rectifier 29, since no control tone is applied to the carrier. In other words, when switch 39-36 is closed, the receiver automatically will be non-responsive to that modulation source which is applied to the carrier concurrently with the monitor tone.

If now the switch arm 39 is shifted so as to close switch 39-37 only the announcements from microphone 8 will be heard, and the receiver will not be responsive when switch 6-5 is closed at the transmitter to apply modulation from microphone 3 on the carrier. This follows from the fact that normally the negative biasing source 35 cuts off amplifier 21. When, however, modulation is applied from source 8 concurrently with the pilot tone, then diode rectifier 32 will develop direct current voltage across resistor 33 which will be applied in a polarity sense such as to oppose the biasing source 35. The amplifier 21 is, therefore, rendered operative. However, the receiver will only be reproducing the modulation from source 8. Hence, the receiver now automatically responds solely to modulation source 8, but does not respond to the other of the modulation sources. From a generic viewpoint, therefore, there has been provided a selective switching mechanism which enables the same monitor tone of super-audible frequency selectively to permit response to one modulation source while preventing response to the other source, or to prevent response to the modulation source combined with the control tone while permitting response to the other modulation source. If desired, different output levels for program and

announcements may be provided, instead of complete elimination of either. In that way, for example, the speech sequences could be at very low level, while the music periods would be of normal level, or the reverse could be had.

The super-audible control tone energy may, also, be utilized to provide acoustic compensation control and/or fidelity control. For either of these functions the direct current voltage developed across resistor 33 by rectifier 32 may be used. Acoustic compensation control is readily provided by connecting the plate circuit of a control tube 41 to the grid circuit of audio amplifier 22 through a path including condenser 42 and coil 43 in series. The plate of tube 41 may be connected to any desired source of positive potential through a proper choke coil. The cathode of tube 41 may be connected to ground through any desired biasing means, such as shown.

The plate to cathode impedance of tube 41 is regulated by connecting the control grid thereof to lead 50 through a switch 45-44. The choke coil 43 has a low impedance to low audio frequencies, while condenser 42 has a low impedance to high audio frequencies. Hence, when switch 45-44 is closed, high negative bias from source 35 biases tube 41 to cut-off. This is the condition when no modulation is being transmitted from source 8. However, when switch 6-10 is closed and modulation from sources 8 and 11 are applied to the carrier, rectifier 32 will function to render tube 41 conductive. This means that the low and high audio notes are bypassed from the grid circuit of amplifier 22. Of course, when the switch 45 is adjusted to the free contact, no control is applied to tube 22.

The fidelity control is provided by a tube 47 which is constructed in the same manner as the acoustic compensation control. There is this difference: the condenser 46, which has a low impedance to high audio frequencies, is arranged in series between the plate of tube 47 and the grid circuit of amplifier tube 23. Switch arm 49 is connected to lead 50, while the contact 48 is connected to the control grid of tube 47. When switch 49-48 is closed, and no control tone energy exists on the carrier, the tube 47 is cut off.

However, when speech from source 8 is applied to the carrier, the control tone energy is rectified and overcomes the biasing source 35. This results in bypassing of the higher audio frequencies. Accordingly, fidelity of reproduction is limited on speech so that stray noise is reduced. It will be understood that the switch arms 39, 45 and 49 are to be adjusted in any desired manner, or sequence. In such case where the microphone 8 is located in a studio where speech programs are constantly delivered, the switch 49-48 is closed so that when the microphone 8 is active in delivering speech to the carrier, there will automatically be developed a limited fidelity of reproduction for the receiver.

While I have indicated and described several systems for carrying my invention into effect, it will be apparent to one skilled in the art that my invention is by no means limited to the particular organizations shown and described, but that many modifications may be made without departing from the scope of my invention.

What I claim is:

In a frequency modulation receiver of the type adapted to receive frequency modulated carrier waves provided with a special control frequency modulation component representative of a desired conditioning of the receiver, the improvement comprising a detector at the receiver to produce the modulation signals of the received waves, means for filtering from the signals current of the special control frequency, means for utilizing the modulation signals, a source of voltage for rendering said utilizing means operative, a rectifier coupled to said filtering means, and responsive to said special control frequency current, to overcome the effect of said voltage source, a second voltage source capable of rendering said utilizing means ineffective, a second rectifier coupled to said filtering means for deriving from the control current a voltage to overcome the effect of said second voltage source, and means for selectively connecting in circuit with the utilizing means either of said rectifiers and its associated one of said two voltage sources.

WINFIELD R. KOCH.
